UNITED STATES PATENT OFFICE

CLARENCE H. HAAS AND LEWIS J. MITCHELL, OF WARREN, OHIO.

STEAM BOILER.

Application filed March 4, 1927. Serial No. 172,759.

The present invention has relation to improvements in steam boilers.

An object of the invention is to direct the flame and other products of combustion against the inner surface of the boiler to retard them in their passage through the same, thus greatly increasing the steaming qualities of the boiler.

The nature of the invention consists in spirally arranged diffusers or baffle plates in the form of pins and corrugations or ribs so as to cause the products of combustion to pass upwardly in a spiral course.

Another important object of the invention lies in the provision of a heater characterized by its inherent simplicity and low cost of construction, and by the fact that it contains a minimum number of parts apt to get out of order from corrosion or otherwise and by the fact that it contains no internal pipe liable to become foul.

With the above and numerous other objects in view, as will appear as the description proceeds, the invention resides in certain novel features of construction, and in the combination and arrangement of parts as will be hereinafter more fully described and claimed.

In the drawing:

Figure 1 is a vertical sectional view through the structure embodying the features of our invention.

Fig. 2 is an enlarged detail sectional elevation thereof,

Fig. 3 is a horizontal section taken substantially on the line 3—3 of Fig. 2,

Fig. 4 is an enlarged detail elevation of the ribs or corrugations.

Now having particular reference to the drawings, our novel boiler constitutes the provision of an open-ended cylindrical shell 5 of desired capacity that is provided at its upper end with a conventional form of head 6 within which is an enlarged central opening 7.

Within the shell 5 at the lower end thereof is an interior shell 8 functioning as the fire box for the boiler. This shell is also of cylindrical formation, being open at its opposite ends and is of slightly less diameter than the diameter of the outer shell 5 providing a water space there-between. The lower end of this interior shell 8 is flared outwardly at 9 that serves as the bottom wall of the boiler while depending therefrom is a skirt 10 that closely engages the

interior of the shell 5 and is suitably secured thereto. The upper end of the interior shell 8 is provided with a conventional head 12 that is also formed with a central circular opening 13 in registration with the opening 7 of the head 6, and within which is arranged one end of a relatively wide cylindrical flue pipe 14, the other end thereof being arranged in said opening of the head 6.

A cylindrical drum 15 is mounted within the interior shell 8 in spaced relation thereto and at its bottom is provided with an inverted conical head 16 and at its upper end with a plane head 17. The upper head 17 is provided centrally with an annular upstanding flange 18 for receiving the tube 19 which rises up through the flue pipe 14 being substantially less in diameter than said pipe. On the cylindrical outer surface 75 of the drum 15 and the tube 19 there are disposed annular ribs 20. These ribs 20 are preferably formed integral with the drum 15 and the tube 19. These ribs are formed in sections as is more clearly illustrated in Fig. 4 so as to provide spirally arranged spaces 21 in which are received spiral fins 22. The spiral fins 22 are wider than the ribs 20 as is clearly illustrated in both Figs. 1 and 2. These fins 20 may actually catch the interior surfaces of the interior shell 8 and the flue pipe 14 if desired and as shown in the drawing. It is to be noted that the spiral of the fin about the tube 19 is opposite to that about the drum.

From the above detailed description it will be seen that the ribs function as baffles to retard the flame, smoke, and other products of combustion in their spiral path caused by the spiral fins 22 about the drum 15 and the tube 19. In this way the maximum heat is obtained from these products of combustion. Thus the boiler will be capable of economical operation and maximum efficiency.

It is thought that the construction, utility, and advantages of this invention will now be apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that after changes in the details of construc-

tion, and in the combination and arrangement of parts may be resorted to without departing from the spirit or scope of the invention as hereinafter claimed or sacrificing any of its advantages.

Having thus described our invention what we claim as new is:

1. A boiler of the class described including, in combination, a fire-box, a flue pipe extending from the fire-box, a tube within the pipe, a drum within the fire-box, means about the drum and about the tube for causing the products of combustion to rise in a spiral path, said means comprising a spirally arranged fin, and a plurality of ribs between the fins, said ribs being circumferentially disposed about the drum and tube.
2. A boiler of the class described including, in combination, a fire-box, a flue pipe extending from the fire-box, a tube within the pipe, a drum within the fire-box, means about the drum and about the tube for causing the products of combustion to rise in a spiral path, said means comprising a spirally arranged fin, and a plurality of ribs between the fins, said ribs being circumferentially disposed about the drum and tube, the bottom end of the drum being of an inverted cone-shaped formation.
3. A diffuser of the character described including a drum, a tube rising from the

35 tube co-axially therewith, a plurality of annular ribs about the drum and about the tube, said ribs being formed in spaced sections, the spaces between the sections forming spiral pathways, and spiral fins in said pathways.

4. A diffuser of the character described including a drum, a tube rising from the 40 tube co-axially therewith, a plurality of annular ribs about the drum and about the tube, said ribs being formed in spaced sections, the spaces between the sections forming spiral pathways, and spiral fins in said 45 pathways, the width of the fins being greater than the width of the ribs.

5. A diffuser of the character described including a drum, a tube rising from the tube co-axially therewith, a plurality of annular ribs about the drum and about the 50 tube, said ribs being formed in spaced sections, the spaces between the sections forming spiral pathways, and spiral fins in said pathways, the width of the fins being greater than the width of the ribs, the spiral of 55 the drum being in an opposite direction from that of the tube.

In testimony whereof they affix their signatures.

CLARENCE H. HAAS.
LEWIS J. MITCHELL.
